(57) **CLAIM**

The ornamental design for a game piece for table tennis table as shown and described.

DESCRIPTION

1.1 : is a top left perspective view of a game piece for table tennis table;

1.2 : is a top right view perspective view thereof; and

1.3 : is a bottom perspective view thereof.

The designs concern gutters that simply attach to the sides of a ping-pong table and collect the balls that fall from it.
